UNITED STATES PATENT OFFICE.

P. H. DRAKE, OF BINGHAMTON, NEW YORK.

DESIGN FOR A BOTTLE.

Specification forming part of Design No. 1,388, dated February 18, 1862.

To all whom it may concern:

Be it known that I, P. H. DRAKE, of Binghamton, in the county of Broome and State of New York, have invented or produced a new and original Design for a Bottle; and I do hereby declare that the following is a full, clear, and exact description of the same, reference being had to the accompanying drawings, making a part of this specification, said drawings being a perspective view of the design.

The design of the bottle is a log cabin or cottage, in which the neck A of the bottle is the chimney. The bilge or portion B, which forms the connection between the neck and body of the bottle, is the roof, which has four inclined sides to give the pitch, and is so molded or formed that it will represent thatch.

C is the body of the bottle, which is of rectangular form, and is so molded or formed that it will represent logs a, placed one over the other and lapped at their ends, as shown at b.

The neck A, it will be seen, has a smooth

surface, is of slightly conical form, and is provided with the usual knob around its upper end or orifice.

The thatch of the roof B is represented by corrugations c, which are at right angles to horizontal shoulders or projections d. The corrugations c represent the straw, and the shoulders or projections d represent the layers of thatch or the lower ends of the same, which project or lap over the upper parts of the layers below them.

Having thus described my invention, what I claim as new, and desire to secure by Letters Patent, is—

The general configuration of the parts herein shown and described, to represent a log cabin or cottage, and constitute a new and original design for a bottle.

P. H. DRAKE.
